(57) **CLAIM**

The ornamental design for the vacuum sealer, as shown and described.

DESCRIPTION

FIG. 1 is a front perspective view of the vacuum sealer;

FIG. 2 is a front view thereof;

FIG. 3 is a rear view thereof;

FIG. 4 is left side view thereof;

FIG. 5 is a right side view thereof; and,

FIG. 6 is a top view thereof.

The broken lines depict portions of the vacuum sealer that form no part of the claimed design.
